US00D558762S

(12) **United States Design Patent** (10) **Patent No.:** **US D558,762 S**
Heath et al. (45) **Date of Patent:** **** Jan. 1, 2008**

(54) **STORAGE DEVICE**

(75) Inventors: **Stephen Robert Heath**, Andover, MA (US); **Aurélie Jouan**, Boulogne-Billancourt (FR)

(73) Assignees: **Koninklijke Philips Electronics N.V.**, Eindhoven (NL); **Swarovski Aktiengesellschaft**, Triesen (LI)

(**) Term: **14 Years**

(21) Appl. No.: **29/275,457**

(22) Filed: **Dec. 27, 2006**

(51) **LOC (8) Cl.** **14-02**

(52) **U.S. Cl.** **D14/356**

(58) **Field of Classification Search** **D14/137, D14/156, 167, 240, 242, 299, 348, 356, 384-385, D14/402, 432-435, 496; 257/315; 439/518, 439/139, 141, 144, 140, 638; 365/63, 131; 710/74, 62; 361/685-6; D11/80-1, 103; D24/102; D9/600, 629**
